TENSION-RELEASER FOR SEWING MACHINES

Harold C. Faulkner, Bridgeport, Conn., assignor to The Singer Manufacturing Company, Elizabeth, N. J., a corporation of New Jersey

Application February 29, 1940, Serial No. 321,495

4 Claims. (Cl. 112—255)

This invention relates to tension-releasers for sewing machines of the type represented in U. S. Patent No. 2,165,016, dated July 4, 1939.

According to the patented construction the tension-releaser is operated by the clutch-mechanism which controls the rapid-feed mechanism of the machine, so that the tension is released when the rapid-feed is thrown in and is restored when the rapid-feed is thrown out. This arrangement is satisfactory in a buttonhole machine which rapid-feeds only at the beginning and end of a buttonhole-producing cycle for the purpose of rapidly moving the work-clamp from buttonhole cutting position into sewing position and from sewing position back to buttonhole-cutting position.

In some machines, however, there is mechanism for throwing in the rapid-feed when the sewing reaches the eye-end of the buttonhole and for throwing out the rapid-feed after the eye-end has been stitched, so that the eye or end stitches of the buttonhole will not pile upon one another at said end. By the eye-end of a buttonhole I mean the end remote from the beginning end where the initial and final stitches are customarily laid. In some buttonholes the stitches at the eye-end are laid radially around an open hole in the work at one end of the buttonhole slit and form an open eyelet at this end of the buttonhole. In other buttonholes, such as are commonly used in coat-lapels, the stitches at the eye-end are laid radially about the end of the buttonhole slit and do not define an open eyelet. It is in sewing these buttonholes of the coat-lapel type that piling of the radial end stitches occurs unless the rapid-feed is thrown in while such stitches are being sewn. The patented tension-releaser above cited will not meet the condition in sewing and rapid-feeding around the eye as the tension on the thread is released whenever the machine is rapid-feeding, whereas, to meet the condition in question, the tension should not be released at any time during the sewing period.

According to the present invention, the operative connection between the rapid-feed clutch-operator and the tension-release lever is disabled by the stop-motion control mechanism, whenever the machine is sewing. Thus, the machine may rapid-feed while sewing around the eye end of the buttonhole under a normal tension. The operation of the rapid-feed clutch-operator will have no action on the tension-releaser while the machine is sewing. This provision also takes care of the desired release of the tension while

rapid-feeding around the eye end of a buttonhole in machines where the stitch-forming mechanism is stopped at the end of the first side-stitching operation and started again at the beginning of the second side-stitching operation on a buttonhole to eliminate the radial end stitches.

In the accompanying drawings, Fig. 1 is a right side elevation of a buttonhole sewing machine embodying the invention. Fig. 2 is a left side elevation of the machine. Fig. 3 is a bottom plan view. Fig. 4 is a rear end elevation, partly in section. Fig. 5 is an inner face view of the pattern-wheel of the machine showing the tripping points and latches for controlling the rapid-feed cross-slide-rod of the machine. Fig. 6 is a perspective view of the lower end of the tension-release lever associated with the rapid-feed-controlling cross-slide-rod and the pattern-wheel which controls the period of operation of the 10 stitch-forming mechanism. Fig. 7 is an outer face view of the pattern-wheel. Fig. 8 is a section on the line 8—8, Fig. 7. Fig. 9 is a top view of the pattern-wheel with the stop-motion-controlling cam-track-follower lever in section and 15 showing the disabling arm for the tension-releasing thrust-bar. Figs. 10 and 11 are fragmentary perspective views of the pattern-wheel with a stop-motion-controlling cam-track eye-section shifted, respectively, to operative and inoperative 20 position. Fig. 12 is a radial section through the pattern-wheel in the region of the shiftable stop-motion-control cam-track section. Fig. 13 is a view of the parts shown in Fig. 6 at the period of 25 a buttonhole-producing cycle when the rapid-feed is thrown in to carry the work from buttonhole-cutting position to sewing position. Fig. 14 is a similar view of the parts immediately prior to the start of a sewing period, showing the tension-release thrust-bar shifted to disabled 30 position. Fig. 15 is a similar view of the parts when the machine is sewing and after the rapid-feed has been thrown out. Fig. 16 is a horizontal section substantially on the line 16—16, Fig. 4, at the start 35 of a buttonhole-producing cycle, the same as in Fig. 6. Fig. 17 is a view similar to Fig. 16 but at the period of the cycle represented in Fig. 14. Fig. 18 is a plan view of the tension-releaser connections on top of the sewing machine bracket-arm. Fig. 19 is a section on the line 19—19, Fig. 18, and Fig. 20 is a section on the line 20—20, Fig. 18.

In the preferred embodiment of the invention illustrated, the machine-frame comprises a hollow box-like bed 1 from one end of which rises

the standard 2 of the overhanging bracket-arm 3 terminating in the head 4.

The stitch-forming mechanism is of the well known type embodying an upper endwise reciprocatory and laterally vibratory needle 5 and under thread mechanism constructed substantially in accordance with the disclosure of U. S. Patent No. 1,372,473, dated Mar. 22, 1921, and comprising a turret 6, Fig. 1, which is turnable about a vertical axis and carries threaded and non-threaded loopers, the former of which is shown at 7, and a pair of loop-detainers one of which is shown at 8. The needle-actuating mechanism is also mounted to turn about a vertical axis coincident with the axis of the turret and the usual turning movements are imparted to the upper needle and under looper mechanisms by the connected upper and lower sector gears 9 and 10, respectively, which are actuated in unison by the usual connections with the cam-groove 11, Fig. 3, in the feed-cam 12. This well known mechanism is more completely shown, for example, in U. S. Patents No. 1,162,207, Nov. 30, 1915; No. 15,324, reissued Apr. 4, 1922, and No. 1,534,017, Apr. 21, 1925. The mechanism operates to rotate the stitch-forming devices in one direction during the sewing around the eyelet-end of a buttonhole and to reversely rotate the stitch-forming devices between sewing periods to restore them to initial position. The stitch-forming devices are actuated from the main sewing shaft 13 which also drives the feed-cam 12 in step-by-step fashion, during the sewing, through the well known pin-and-star-wheel drive 14, Fig. 3, and the usual train of gears 15, such as more completely shown in said U. S. Reissue Patent No. 15,324.

The work-clamp is of the travelling type. It is first rapidly moved over the bed 1 to carry the work forwardly from initial or buttonhole-cutting position to stitching position, then more slowly moved in step-by-step fashion to place the stitches about the buttonhole, and then rapidly returned to initial position. It is constructed substantially in accordance with said U. S. Reissued Patent No. 15,324 and comprises the lower clamp-plates 16 and upper clamping feet 17 which are depressed into clamping engagement with the work by a rocking movement of two connected coaxial rock-shaft sections 18, 18' to the former of which is connected an arm 19, Fig. 1, adapted to be depressed by the usual clamp-closing lever 20 actuated at the beginning of a buttonhole-making cycle by a cam-groove 21, Fig. 4, in a continuously running pulley 22 loose on the buttonhole-cutter shaft 90. A slide-pin 23, carried by the rearwardly extending arm 24 of the clamp-closing lever, is permitted to enter the cam-groove 21 for one revolution of the pulley 22, whereupon it is ejected and latched in ejected position, as explained in U. S. Patent No. 1,832,665, Nov. 17, 1931; the present clamp-closing mechanism being constructed substantially in accordance with the disclosure in said U. S. Patent No. 1,832,665.

The clamp-plates 16 are carried by the cross-slide plate 24', Fig. 3, which, in turn, is carried by the longitudinal slide-frame 25 to which travelling movements are imparted by the link-connection 26, Fig. 3, with the longitudinal feed-lever 27 having a follower working in a longitudinal feed-cam groove in the feed-cam wheel 12. The cross-slide plate 24' is shifted by the lever 28, Fig. 3, which has the usual connections with the feed-cam 12 and removable pattern-

wheel 29 on the cross-shaft 30 which is geared at 31, Fig. 1, to the feed-cam 12, so as to run with the latter. The present feed-mechanism is constructed substantially in accordance with the disclosure of said U. S. Reissue Patent No. 15,324.

The period of operation of the stitch-forming mechanism is controlled by the conventional start- and stop-lever S which carries a stop-tooth 32 adapted to enter a stop-notch 33 in the stop-cam 34 on the sewing shaft 13. The stop-lever S is carried by a rock-shaft 35 which, when turned to swing the lever and its stop-tooth 32 rearwardly from the stop-cam, effects the coupling thereto of the constantly running belt-driven pulley 36 through a conventional clutch-mechanism (not shown). This start- and stop-control mechanism is the same as that shown in said U. S. Patent No. 15,324; reissued Apr. 4, 1922. To operate the start- and stop-control lever S, the rock-shaft 35 has fixed thereto an arm 31 which is connected by a link 38 to a lever 39 which is pivoted at 40 on the bed 1 and has a nose 41 which rides on the cam-track 42 of the pattern-wheel 29. This cam-track 42 has high and low circular portions which are separated by the start-sewing cam-rise 43 and the stop-sewing drop-off shoulder 44, as is fully explained in said reissued patent.

In the pattern-wheel 29 of the present machine, however, the cam-track 42 has a shiftable plate-section 45 which is movable axially of the pattern-wheel 29 to carry it from its full line or operative position, Fig. 12, to its dotted line or inoperative position. When in full line position, the plate-section 45 of the cam-track 42 bridges the gap between the supplemental start-sewing cam-rise 46 and stop-sewing shoulder 47, Figs. 10 and 11, and renders these ineffective. When the plate 45 is shifted to dotted line position, Fig. 12, which is the position shown in Fig. 11, the plate 45 is carried to one side of the follower-nose 41 and does not engage the latter. Thus the cam-rise 46 and shoulder 47 are rendered operative upon the follower-nose 41 and the sewing is stopped at the end of the first side-stitching operation on the buttonhole and started again at the beginning of the second side-stitching operation; the stitch-forming mechanism being stopped while the machine is rapid-feeding around the eye-end of the buttonhole.

The plate 45 is carried by the slide-shaft 48 of the knob 49 and is steadied by the pins 50 which are fixed in the body of the pattern-wheel 29. The plate 45 is confined in either of its two positions by the spring-influenced latch-lever 51, see particularly Fig. 12. Thus the machine may be quickly converted from one which sews around the eye-end of a buttonhole to one which stops sewing while turning around the eye-end of the buttonhole and then starts sewing again after the eye-end of the buttonhole has been passed.

The rapid-feed of the work-clamp from buttonhole-cutting position to sewing position and return is effected by the usual constantly running rapid-feed drive-shaft 52, which, through a worm-and-gear reduction 53, Fig. 1, drives the live element 54, Fig. 3, of a clutch, the driven element 55 of which is fast on the cross-shaft 30. It will be understood by referring to said U. S. Reissue Patent No. 15,324 that the withdrawal of the cone 56 from the driven clutch-element 55 effects engagement of the driving and driven clutch-elements 54, 55, while projection of the cone 56 toward the driven clutch-element 55 effects the de-clutching of the parts 54, 55. The

cone 56 is actuated by the usual arm 57 rigidly mounted on the cross-slide rod 58 and carrying the lateral pin 59 and latching block 60, Fig. 4.

As disclosed in U. S. Patent No. 1,548,815, Aug. 11, 1925, there is mounted in the base 1 on the bracket 61, a continuously rocking bell-crank lever 62, 63, the forked arm 62 of which embraces a crank 64 on the rapid-feed shaft 52. Pivoted on the arm 63 is a single reciprocating bar 65 the free end of which has connected to it a spring 66, which pulls the bar 65 upwardly against the seat 67 of the latch 68, Fig. 5, pivoted at 68 on the bed 1. The bar 65 reciprocates idly when held down by the latch 68. When the latch 68 is swung on its pivot 69 to release the bar 65, the latter is drawn upwardly by the spring 66 and the shoulder 70, Fig. 4, engages the pin 59 and pushes the cross-slide rod 58 to the right against the resistance of the recovery spring 71 to withdraw the cone 56 from the clutch-element 55 and effect the coupling of the rapid-feed shaft 52 to the cross rotary shaft 30 to drive the feed-cam 12 at its rapid rate. When the slide-rod 58 is pushed to clutch-engaging position, it is held there by engagement of the shoulder 72, Fig. 4, on the lever 73 with the latch-block 60; the lever 73 being biased upwardly about its fulcrum 74 by the spring 75. Thus, the lever 73 and shoulder 72 act as a spring-latch to hold the slide-rod 58 in clutch-engaging or rapid-feed position. During the return movement of the bar 65 the inclined shoulder 76, Fig. 4, engages the pin 59 and causes the bar 65 to be depressed sufficiently to be re-engaged in idling position by the latch-lever 68.

The pattern-wheel 29 which is removably carried by the cross rotary shaft 30 and operates the stop-motion lever S through the lever 39 and link 38 to control the period of action of the stitch-forming mechanism, also adjustably carries, on its inner face, the tripping points 77, 78 and 79, Fig. 5, which tilt the lever 80 and control the throwing out of the rapid-feed drive for the feed-wheel 12. The lever 80 is forked at one end to embrace the end 81 of the latch-lever 73. Hence, when the lever 80 is tilted by one of the tripping points 77, 78, 79, the latch-lever 73 is depressed and the slide-rod 58 released, whereupon the spring 71 on the slide-rod 58 acts to shift the slide-rod 58 from rapid-feed running position, Fig. 17, to rapid-feed stopping or de-clutching position, Fig. 16.

Tripping point 77 throws out the first rapid-feed motion of the work-clamp from starting position when the work-clamp reaches sewing position. Tripping point 78 throws out the rapid-feed at the eye, when used, and tripping point 79 throws out the final rapid-feed when the work-clamp is returned to starting position.

The controlling mechanisms for initiating the rapid-feed prior and subsequent to the sewing period are substantially the same as those disclosed in U. S. Patent No. 1,548,815 and comprise the rock-shaft 82, having an arm 83 engaging the latch 68, another arm 84 adapted to be depressed by operation of the depending arm 85 of the clamp-closing lever, and a third arm 86 adapted to be elevated by the pawl 87 actuated by vertical motion of the stop-tooth 32 of the stop-motion device S.

The present machine is of the cut-after type, that is, it cuts the buttonhole after stitching it. The buttonhole-cutting mechanism is conventional and embodies the travelling buttonhole-cutter levers 88, 89, Fig. 2, which are given their

customary travelling and closing-and-opening movements by suitable cams on the cutter-shaft 90 to which a single rotation is imparted prior to stitching by the continuously rotating pulley 22 acting through the usual one-revolution clutch on the clutch-disc 91.

The present machine has mounted on top of the standard and bracket-arm a housing 92 for a take-up cam 93 which is mounted on a shaft 94 driven by the top-shaft 95 which actuates the needle-bar 96 in the usual manner. Pivotedly mounted at 97 in the housing 92 is the take-up lever 98 carrying a follower roll 99 which enters the take-up cam-groove 93. The take-up lever 98 has at its free end a thread-eye 100 which acts upon the needle-thread between the tension-device 101 and the hollow needle-bar 96 through which the needle-thread runs to the needle 5. The course of the needle-thread is the same as shown in said U. S. Patent No. 2,165,016. The tension-device 101 is conventional and, in addition to the two tension-disks 101', comprises the arbor 102 on which the tension-disks 101' are mounted. The arbor has a diametrical slot 103 at one end to pass the diameter-bar 104 of the pressure-head 105 against which one end of the beehive-spring 106 rests; the other end of such spring being engaged by the adjustable thumb-nut 107. The arbor 102 has in its un-slotted end an axial hole to admit the tension-release pin 108 which, at times, engages the diameter-bar 104 of the presser-head 105 and pushes the latter away from the tension-disks 101' to release the tension on the needle-thread. The tension-release pin 108 is in position to be engaged by one end of the lever 109, Fig. 18, fulcrumed at 110 on the under side of the cover 111 for the take-up housing 92. The lever 109 has at one end a bent up tongue 112 in position to be engaged by the head of the screw 113 adjustably threaded into the upper end of the tension-release lever 114 which is fulcrumed at 115 to a bracket 116 mounted on the left side of the bracket-arm standard 2. The tension-release lever 114 also has on it a cam-follower nose 117 which, at times, is engaged by a tension-releasing cam-block 118 adjustably mounted on the rod 119 connected to the longitudinal slide-frame 25 of the work-clamp. The tension-release lever 114 has fastened to it a downward extension 120 having an offset lower end portion 121 that terminates above the outer end of a thrust-bar 122 which is freely pivoted on the pin 59 carried by the rapid-feed clutch-controlling cross-slide rod 58. The thrust-bar 122 has at its upper edge a thrust-shoulder 123 which, at times, engages the lower end of the tension-release lever 114-120-121 and moves it in a direction to release the tension. The thrust-bar 122 is tied by a spring 124 to the offset lower end 121 of the tension-release lever, so that the thrust-bar is spring-urged upwardly at all times. The lever 39 which carries the cam-track-follower-nose 41 also has fixed thereto an arm 125 that overhangs the free end of the thrust-bar 122 and, when the follower nose 41 is riding on the high part of the cam-track 42 or, in other words, when the sewing mechanism is in operation, the thrust-bar 122 is disabled or held by the arm 125 in a depressed position out of possible engagement with the tension-release lever 114-120-121. The present machine is fitted with a device, such as represented in the U. S. patent application of Edward P. Spaine and Harold C. Faulkner,

Serial No. 243,126, filed Nov. 30, 1938, for tripping the rapid-feed into action when the sewing operation reaches the eye-end of the buttonhole. To this end there is fixed to the rock-shaft 82 an arm 126 which is within the range of travelling movement of the tripping point 127 on the block 128 carried by the rod 119. At the end of the first side-stitching operation on the buttonhole, the tripping point 127 engages and depresses the arm 126 thus releasing the latch 68 from the rapid-feed-clutch-controlling push-bar 65 and throwing in the rapid-feed. The tripping point 127 may be turned to an inoperative position and held there by the latch 128', when so desired, as explained in said copending application.

Operation

At the beginning of a buttonhole-producing cycle the tension-release lever 114 is held in tension-release position by the block 118, Fig. 16, which at that time is under the nose 117 of that lever. Also, the shoulder 123, Fig. 6, of the thrust-bar 122 is spaced inwardly from the offset lower end 121 of the tension-release lever. The thrust-bar 122 is, however, held by the spring 124 against the lower end 121 of said lever.

When the machine is started the clamp-closing lever 20—24—85 is first given its usual rocking impulse and, during the recovery motion of this impulse, the arm 85 depresses the arm 84 of the rock-shaft 82 and trips the rapid-feed into action. When the slide-rod 58 is moved from the position of Fig. 6 to the position of Fig. 13, to throw in the rapid-feed, the shoulder 123 of the thrust-bar 122 is moved up to the tension-release lever-end 121 to hold the tension released after the rapid-feed of the work-clamp has carried the block 118 out from under the nose 117 of the tension-release lever. The rapid-feed continues until the work-clamp has been carried to sewing position whereupon the start-sewing cam-rise 43 of the pattern-wheel cam-track 42 engages the nose 41 of the follower-lever 39 and shifts the stop-lever S to start the stitch-forming mechanism. The shift of the lever 39 by the cam-rise 43 causes the arm 125 to depress the thrust-bar 122 to its ineffective or disabled position, Fig. 14, and release the lever 114—120—121, thereby restoring the tension on the needle-thread. At the same time the tripping point 11 on the back of the pattern-wheel throws out the rapid-feed.

Assuming that the cam-track plate-section 45 is set in full line position, Fig. 12, so as to engage the follower-nose 41 to continue the sewing around the eye-end of the buttonhole, the sewing will progress all the way around the buttonhole without being stopped. The rapid-feed will be thrown in at the eye of the buttonhole by the action of the tripping point 127 but will have no effect upon the thread-tension for the reason that the tension-releasing thrust-bar 122 is held disabled by the arm 125 on the pattern-wheel cam-track follower-lever 39, as shown in Fig. 15. At the completion of the sewing period, the nose 41 on the lever 39 drops off of the stop-sewing pattern-wheel cam-track shoulder 44 and releases the thrust-bar 122 which is immediately restored by the spring 124 to operative position. The rapid-feed is now tripped into action by the pawl 87 associated with the stop-motion device S and the action of the rapid-feed-starting slide-rod 58 causes the thrust-bar 122 to move the lever 114—120—121 and release the tension. The movement of the work-clamp back to starting position carries the cam-block 118 back

under the nose 117 of the tension-release lever 114 to hold the tension released after the rapid-feed clutch-controlling slide-rod has been moved back by the spring 71 to stop the rapid-feed at the completion of the buttonhole-producing cycle.

The cam-block 118 is of sufficient width to hold the lower end 121 of the tension-release lever slightly spaced from the shoulder 123 of the thrust-bar 122, as shown in Fig. 13. The link 38 of the stop-motion control mechanism has a toggle-section 38', Fig. 2, with a handle 38'' whereby the toggle may be broken to withdraw the lever 39 and its cam-follower nose 41 sufficiently to permit the pattern-wheel 29 to be readily removed from and replaced on its shaft 30. This toggle-device is substantially the same as that disclosed in said U. S. Patent No. 1,548,815.

When the toggle-link 38' is manipulated to swing the lever 39 rearwardly for removal of the pattern-wheel 29, the arm 125 on the lever 39 depresses the thrust-bar 122 to an ineffective position. When the pattern-wheel 29 is replaced and the toggle-link 38' is restored to its initial position, the lever-arm 125 is elevated and releases the thrust-bar 122 which is restored by its spring 124 to its original position with the shoulder 123 in position to be engaged by the tension-release lever end 121 when the cam-block 118 is carried out from under the lever-arm 114.

If it is desired to omit the sewing at the eye of the buttonhole, the pattern-wheel cam-track plate 45 is shifted to dotted line position, Fig. 12, where it does not engage the follower nose 41. This shift of the plate 45 renders operative the supplementary stop-sewing shoulder 47 and start-sewing cam-rise 46. Under this adjustment the sewing mechanism will be stopped and the rapid-feed thrown in when the eye is reached. The tension will also be released. After rapid-feeding around the eye, the rapid-feed will be thrown out, the tension will be restored and sewing will be resumed.

The pattern-wheel 29, follower-lever 39, link 38 and lever S constitute automatic means (A), Fig. 6, to start and stop the stitch-forming mechanism, while the spring influenced thrust-bar 122 constitutes means (B) actuated by the rapid-feed-controlling mechanism or cross-slide rod 58 for operating the tension-release lever 114—120—121 to release the tension 101 while the rapid-feed is in operation. The arm 125 fixed to the follower-lever 39 constitutes means governed by automatic means (A) for disabling means (B) while the stitch-forming mechanism is in operation.

Having thus set forth the nature of the invention, what I claim herein is:

1. In a sewing machine of the buttonhole type having stitch-forming mechanism, a stop-motion device therefor, automatic controlling mechanism for the stop-motion device, a work-holder, stitching-feed mechanism for relatively moving the stitch-forming mechanism and work-holder in sewing around a buttonhole, rapid-feed mechanism for relatively moving the stitch-forming mechanism and work-holder at a faster speed during portions of a buttonhole-producing cycle, controlling means for the rapid-feed mechanism, a sewing thread tension-device, and a tension-releaser operatively connected to the controlling means for the rapid-feed mechanism, the improvement which consists in the provision of means operated by the stop-motion controlling mechanism to disable the operative connection between the tension-releaser and the rapid-feed

controlling mechanism whenever the machine is sewing, so that the thread-tension will not be released while the machine is sewing, in case the rapid-feed is thrown in during a portion of the sewing period to avoid overcrowding of stitches.

2. A buttonhole sewing machine having stitch-forming mechanism, a stop-motion device therefor, a pattern-wheel having a cam-track, a follower-lever acted upon by said cam-track and connected to the stop-motion device to control the period of operation of the stitch-forming mechanism, a work-holder, stitching-feed mechanism for relatively moving the stitch-forming mechanism and work-holder in sewing around a buttonhole, rapid-feed mechanism for relatively moving the stitch-forming mechanism and work-holder at a faster speed during certain periods of a buttonhole-producing cycle, a rapid-feed clutch for starting and stopping the rapid-feed, a clutch-operating slide-rod, a thread-tension device, a tension-release lever terminating adjacent one end of said slide-rod, a thrust-bar connected to said slide-rod and adapted to engage and shift said tension-release lever to release the tension when the slide-rod moves to throw in the rapid-feed, and an arm on the stop-motion-controlling cam-track-follower-lever arranged to hold said thrust-bar in an ineffective position when said follower-lever is shifted in a direction to start the sewing operation.

3. In a buttonhole sewing machine, stitch-forming mechanism, a thread-tension device, automatic means (A) to start and stop the stitch-

forming mechanism, a work-holder, stitching-feed mechanism to relatively move the stitch-forming mechanism and work-holder in sewing about a buttonhole, rapid-feed mechanism and automatic controlling means therefor to relatively move the stitch-forming mechanism and work-holder at a faster speed during certain periods of a buttonhole-producing cycle, means (B) actuated by the rapid-feed controlling mechanism to release said thread-tension device while the rapid-feed is in operation, and means governed by said automatic means (A) to disable said means (B) whenever the stitch-forming mechanism is in operation.

4. A buttonhole sewing machine having stitch-forming mechanism, a work-holder, stitching-feed mechanism to relatively move the stitch-forming mechanism and work-holder in sewing about a buttonhole, rapid-feed mechanism to relatively move the stitch-forming mechanism and work-holder at a faster speed during certain portions of a buttonhole-producing cycle, a shiftable member to control the starting and stopping of the rapid-feed mechanism, a thread-tension device, a tension-release lever, a thrust-bar pivotally carried by said shiftable member in position to engage and operate said tension-release lever, automatic stop-motion mechanism to control the period of operation of the stitch-forming mechanism, and means controlled by said stop-motion mechanism to shift said thrust-bar to an ineffective position whenever the stitch-forming mechanism is in operation.

HAROLD C. FAULKNER.
